Primary Examiner — Carol P Rademaker(74) *Attorney, Agent, or Firm* — Smith, Gambrell & Russell, LLP(57) **CLAIM**

The ornamental design for a bottle, as shown and described.

DESCRIPTION

FIG. 1 is a front elevational view of a bottle showing the claimed design, the rear elevational view being identical;

FIG. 2 is a right side elevational view thereof, the left side elevational view being identical;

FIG. 3 is a detail of a portion of the claimed design taken from FIG. 2, shown at an enlarged scale;

FIG. 4 is a top plan view of the bottle of FIG. 1, shown at a reduced scale;

FIG. 5 is a detail of a portion of the claimed design taken from FIG. 4, shown at an enlarged scale;

FIG. 6 is a bottom plan view of the bottle of FIG. 1, shown at a reduced scale; and,

FIG. 7 is a top, front, right side perspective view of the bottle of FIG. 1 thereof, shown with the cap removed.

The dash-dash-dash-dash type broken lines shown in the drawings are included for the purpose of illustrating environmental structure and form no part of the claimed design.

The dot-dash-dot-dash type broken lines shown in the drawings define the boundaries of detail portions of the claimed design and form no part of the claimed design.
